FOUNTAIN PEN

Filed Oct. 26, 1945

UNITED STATES PATENT OFFICE

2,474,389

FOUNTAIN PEN

Russell T. Wing, Excelsior, Minn.

Application October 26, 1945, Serial No. 624,793

11 Claims. (Cl. 120—46)

1

This invention relates to fountain pens and it has to do more particularly with fountain pens of that type embodying ink feed means including an overflow ink collector such as disclosed in my U. S. Letters Patent No. 2,187,528, issued January 16, 1940, and U. S. Letters Patent No. 2,223,541, issued December 3, 1940, to Marlin S. Baker.

Pens of the foregoing character embody various forms of ink reservoirs and filling mechanisms therefor. In some instances the barrel may comprise the ink reservoir with provision for filling as disclosed in the above-mentioned Baker patent or U. S. Letters Patent No. 1,904,358, issued to Arthur O. Dahlberg on April 18, 1933. In other instances the reservoir may comprise the usual ink sac adapted to be filled in any other well known manner. In use of pens of the foregoing type it is necessary that the overflow ink collector of the feed means be substantially cleared of ink after the ink reservoir is filled in order that it be conditioned to immediately thereafter serve its intended purpose of collecting ink that may flow from the reservoir in excess of that required for writing purposes. For example, filling mechanisms of the type shown in said Baker patent includes a reciprocable plunger for actuating the filling mechanism and it has been required that the user remove the pen from the ink at the end of the filling operation with this plunger depressed and that the plunger then be released to withdraw ink from the collector into the reservoir. While this manipulation well serves its intended purpose, neglect by users in following instructions in certain instances has resulted in difficulties due to the fact that the collector was not conditioned following the filling operation to properly take care of overflow of ink from the reservoir. The principal object of my invention is to eliminate the foregoing condition by providing an arrangement wherein the collector is substantially cleared of ink in the course of the normal operations necessarily carried out by the user in filling the pen—special manipulation of any kind by the user being avoided.

In pens of the foregoing character it is customary to enclose the manually actuatable part of the filling mechanism, such as a reciprocable plunger, by a cap which is removed when it is desired to fill the pen and replaced when the filling operation is completed. Another object of my invention is to provide means controlled by the replacement of the cap just referred to for substantially clearing the collector of ink.

2

Additional objects are to provide means positively preventing completion of the final stroke of the filling mechanism until the usual closure cap therefor is replaced, which replacement is a normal and customary procedure carried out after the pen is removed from the ink following the filling operation; to eliminate all dependence upon the attentiveness of the user to filling instructions; and to provide an improved fountain pen having all of the foregoing features which is of simple and rugged construction and which serves its intended ink feed functions with a maximum degree of efficiency.

The invention further consists in the several features hereinafter set forth and more particularly defined by claims at the conclusion hereof.

In the drawings:

Fig. 1 is a vertical sectional view through a fountain pen embodying the invention;

Fig. 2 is an enlarged detailed sectional view of the filling mechanism showing it at the end of its stroke;

Fig. 3 is a view similar to Fig. 2 showing the filling mechanism after completion of the filling operation and before the cap is screwed down;

Fig. 4 is a detailed perspective view of the plunger locking detent;

Fig. 5 is a vertical sectional view taken on the line 5—5 of Fig. 3.

Referring to the drawings, the pen includes a tubular barrel 6 of suitable plastic material having a forward externally threaded reduced barrel extension 7 and an internally threaded rear end 8. The interior of the barrel, intermediate its ends, constitutes a reservoir 12. The forward end of the barrel 6 supports a feed mechanism in communication with the ink reservoir 12, and the rear end of the barrel supports a filling mechanism, both of which mechanisms will be described more in detail hereinafter.

The ink feed mechanism includes a cellular type overflow ink collector 13, a tubular pen nib 14, a feed bar 15, and an outer shell 16. The ink collector 13 is adapted to embrace and support the tubular nib 14 and the feed bar 15, and these parts which are adapted to be assembled as a unit in the extension 7 are covered by the shell 16 except for the writing point of the nib 14. The parts 13, 14, 15 and 16 are formed, constructed and arranged similar to the parts 30, 31, 32 and 33 of the aforementioned Baker Patent No. 2,223,541 and function in a similar manner to control the flow of ink from the pen. The only change in detail of the present construction of

the parts above described over that of said Baker patent is a continuation of the narrow slit 40 of said patent structure completely across the reduced diameter portion of the collector as indicated herein by the numeral 17. As the novelty of the present invention is not in the details of the ink feed mechanism per se but only in the association of a collector type feed mechanism with the filling mechanism, further description thereof is deemed unnecessary.

The filling mechanism includes a so-called breather tube 18 which is mounted at its front end in a bore 19 of the feed bar 15 and which corresponds to the bore 32^a of said Baker Patent 2,223,541 and further includes an expandable chamber type filling device having a reciprocatory operating member, preferably a reciprocatory plunger 20. The specific filling mechanism herein shown is of the general character disclosed in U. S. Letters Patent No. 1,904,358, granted on April 18, 1933, to Arthur O. Dahlberg, and includes a flexible diaphragm 21, means for clamping the diaphragm to the barrel 6, the plunger 20, means connecting the inner end of the plunger with the central portion of the diaphragm, spring means for returning the plunger and diaphragm on its suction stroke, and further includes according to this invention means for automatically stopping or preventing said plunger moving the full length of its stroke during the filling of the pen by the operator, and means controlled by the cover cap for the plunger to release such stopping means to permit the plunger to complete its stroke and thus withdraw from the collector device any ink that may have been deposited therein during the filling operation.

The diaphragm 21 is a thin disk of rubber or other suitable inkproof flexible material, and the means for clamping it to the barrel comprises a sleeve 22 having its inner end 23 tapered to correspond to the tapered bore of a sleeve 9 with the outer edge portion of said disk wedged or clamped between said tapers to form a fluid tight joint by the clamping of the sleeve 22 by means of a sleeve clamping nut 24 having a threaded portion 25 engaging the threaded end 8 of the barrel and having a threaded outer end 26 to fit the internally threaded end 27 of a plunger cover cap 28.

The means connecting the inner end of the plunger 20 with the central portion of the diaphragm 21 includes a ball 29 between which and the inner flanged end 30 of the plunger 20 and a plug or collar 31 having a press fit therein the central portion of said diaphragm is clamped.

The filling plunger 20 is a hollow tubular member which is guided in the bores 32 and 33 formed in the sleeve 22 and the nut 24, respectively, with its outer end having an upset connection 34 with a flanged collar 35. The spring means for returning the plunger on its suction stroke includes a spring 36 interposed between the head 37 of a detent or latch 38 and a key or bar 39 that works in diametrically disposed and elongate slots 40 in the plunger 20 and is anchored at its ends in openings 41 in the sleeve 22.

The latch 38 has a latching blade or tongue 42 provided with a right-angled locking or stop shoulder 43 adapted during normal filling operations of the pen by the operator to engage the bar 39 and thus stop the movement of the plunger before it moves the full length of the slots 40, as shown in Fig. 3. The latch 38 has an offset extension 44 beyond the shoulder 43 which rides along under the bar 39 during movement of the plunger 20 between the positions shown in Figs. 1

and 3 respectively and thus maintains the latch 38 in position whereby the shoulder 43 engages the bar 39 when the plunger 20 is moved into the position shown in Fig. 3. Hence when the cap 28 is removed and the plunger 20 is pushed inwardly against the opposing force of the spring 36 from the position shown in Fig. 1 to the position shown in Fig. 2, the plunger travels the full length of its stroke and for succeeding strokes in the ordinary filling of the pen the plunger makes a partial stroke between the position shown in Fig. 2 and the position shown in Fig. 3, and at the completion of the filling operation by the operator, the plunger is moved outwardly by the spring 36 and held by the latch 38 in the partial stroke position shown in Fig. 3.

To permit release of the locked plunger 20 from its partially complete outstroke position to effect an additional suction action the cover cap 28 has a latch release member 44 in the form of an inwardly extending centrally disposed rod. As the cap is screwed onto the barrel nut 24 the latch release member 44 passes through the opening 46 in the collar 35 and an opening 47 in the head 37 of the latch 38 and engages an inclined side or cam face 48 on said latch member 38, and in doing so cams the tongue 42 outwardly through the tilting of said head relative to the collar 35. The tongue is thereby moved laterally relative to said bar 37 a distance sufficient to release its shoulder 43 from said bar and allow spring 36 to move the plunger 20 to the end of its out stroke and in so doing create a sufficient void in the reservoir to allow ink that may have collected in the collector 13 to be drawn into the reservoir.

Thus the collector device is cleared of ink, so that it may function as intended without any special manipulation of the filling mechanism by the operator.

I desire it to be understood that this invention is not to be limited to any particular form or arrangement of parts except as limited by the prior art and by the appended claims.

I claim:

1. In a fountain pen of the type described a barrel having an ink reservoir therein, an ink feeding passage communicating with said ink reservoir, an overflow ink collector also communicating with said ink reservoir, operating means for filling said ink reservoir, a cap adapted to be attached to the rear end of said barrel, said operating means being normally operable, with said cap removed, between limits of operation to cause said ink reservoir to be reduced to a minimum capacity and enlarged to a capacity less than maximum capacity, and means including a part on said cap and a part on said operating means for transmitting motion from said cap to said operating means in response to movement of said cap on said barrel toward its closed position on said barrel for actuating said filling means to cause said ink reservoir to be enlarged to its maximum capacity whereby ink is drawn from said collector into said reservoir.

2. In a fountain pen of the type described feed means comprising an overflow ink collector, a barrel containing an ink reservoir in communication with said feed means, filling means for expanding and contracting the volume of said reservoir, a latch comprising coacting parts on said barrel and said filling means limiting the movement of said filling means during normal filling operation, a cap adapted to be detachably connected to said barrel, and a part on said cap positioned to engage said latch upon movement,

of the cap on said barrel toward its connected position on said barrel to release said latch whereby to extend the limit of movement of said filling means in a direction to further enlarge said ink reservoir and draw ink from said collector into said reservoir.

3. In a fountain pen of the type described comprising a barrel having an ink reservoir therein, a feed means at the front end of said barrel in communication with said reservoir, and a filling mechanism having a plunger within said barrel and reciprocable lengthwise thereof to vary the effective volume of said reservoir for filling the latter, and wherein said feed means includes an overflow collector, and means for insuring clearance of said collector at the completion of each filling operation, said last-named means including a cap adapted to be connected to the rear end of said barrel and removable to provide access to said plunger and latch means comprising coacting parts on said plunger and said barrel which limits movement of said plunger short of a full rearward stroke with respect to said barrel to prevent enlarging the effective volume of said reservoir beyond a predetermined amount, and an element on said cap adapted to contact said latch means to disconnect the same upon movement of said cap on said barrel towards its connected position on the rear end of said barrel whereby full rearward stroke of said plunger is permitted to thus enlarge the effective volume of said reservoir beyond said predetermined amount.

4. In a fountain pen, an elongate, hollow barrel, feed means at the front end of said barrel, said feed means being operative to absorb a substantial quantity of ink during each pen-filling operation and to retain the same subject to withdrawal as hereinafter described, said barrel having an interior chamber constituting an elongate ink-holding reservoir at the rear of said feed means and in communication therewith, a filling device comprising a plunger disposed within and reciprocable lengthwise of said reservoir, a cap detachably connected to the rear end of said barrel and removable to provide access for operating said plunger, said plunger being normally operative with said cap removed between limits of movement corresponding to a predetermined minimum effective volume of said ink-holding reservoir and an enlarged volume less than maximum effective volume thereof, and coacting parts on said cap and said filling device adapted to transmit motion to said filling device when the cap is moved on said barrel toward its normal, replaced position on said barrel whereby said plunger is moved to provide maximum effective volume of said ink reservoir, whereby, when the front end of the pen is removed from the ink supply, the ink is drawn from said collector into said reservoir.

5. A fountain pen having a barrel, a reservoir therein including a displaceable member, ink feeding passage means communicating with said reservoir, operating means for said displaceable member, and a cap adapted to be removably attached to said barrel, said operating means being normally movable, with said cap removed, between limits of operation whereby said displaceable member is either displaced to its fullest extent to reduce the effective volume of said reservoir to a minimum or partially displaced whereby the effective volume of said reservoir is less than maximum, said cap having a portion adapted to cooperate with said operating means to impart movement thereto as said cap is itself

moved on said barrel towards its normal, replaced position on said barrel whereby the displaceable member is moved to enlarge the effective volume of said reservoir to its maximum extent after filling.

6. In a fountain pen having a barrel, a reservoir including a displaceable member in said barrel, a cap for the rear end of said barrel and ink feed mechanism including a collector device, 10 the combination with said displaceable member, of a reciprocatory plunger for operating said member to draw ink into said reservoir, stop means comprising coacting parts on said barrel and said plunger to limit the stroke of said plunger 15 when said cap is removed to less than full stroke at the end of the filling operation by the operator whereby the effective volume of said reservoir is reduced to a minimum and enlarged to a degree less than maximum, and means comprising 20 a part on said cap adapted to release said stop means upon movement of said cap on said barrel towards its connected position on said barrel whereby said plunger is allowed to complete its full stroke and thereby cause said displaceable member to enlarge the effective volume 25 of said reservoir to a maximum and thus draw ink from said collector into said reservoir.

7. In a fountain pen having a barrel, a reservoir including a displaceable member in said barrel, a cap for the rear end of said barrel and ink feed mechanism including a collector device, the combination with said displaceable member, of a reciprocatory spring-returned plunger for operating said displaceable member to draw ink into said reservoir, and releasable stop means including coacting parts on said plunger and said barrel adapted to hold said plunger in partially completed return stroke position at the end of the filling operation by the operator, said cap carrying 30 a contact member adapted to engage said stop means to release the same upon movement of said cap on said barrel toward its connected position on said barrel allowing the plunger to return to its full return stroke position by the 35 action of said spring whereby said displaceable member is operated to draw ink from said collector device into said reservoir.

8. In a fountain pen having a barrel, a reservoir including a displaceable member in said barrel, a cap for the rear end of said barrel and ink feed mechanism including a collector device, the combination with said displaceable member, of a reciprocatory spring-returned plunger for operating said member to draw ink into said reservoir, 50 and releasable latch means including coacting parts on said plunger and said barrel adapted to hold said plunger in partially completed return stroke position at the end of the filling operation by the operator, said cap carrying a contact member adapted to engage said latch means to release the same upon movement of said cap on said barrel toward its connected position on said barrel allowing the plunger to return to its full return stroke position by the 55 action of said spring whereby said displaceable member is operated to draw ink from said collector device into said reservoir.

9. In a fountain pen having a barrel, a reservoir including a displaceable member in said barrel, a cap for the rear end of said barrel, and ink feed mechanism including a collector device, the combination with said displaceable member, of a reciprocatory plunger, a spring within said plunger for moving the same on its out stroke, a stop in said barrel, a latch member having a

part interposed between said plunger and spring and automatically engageable with said stop as said plunger moves on its out stroke to hold said plunger in partially completed stroke position, and a member carried by said cap adapted to engage said latch upon movement of said cap on said barrel toward its connected position on the barrel to move the latch out of engagement with said stop means to allow the spring to move said plunger to its full out stroke position and thereby cause said displaceable member to draw ink from said collector device into said reservoir.

10. In a fountain pen having a barrel, a reservoir including a displaceable member in said barrel, a cap for the rear end of said barrel, and ink feed mechanism including a collector device, the combination with said displaceable member, of a reciprocatory plunger having diametrically disposed slots, a stop bar carried by the barrel and extending through said slots, a spring within said plunger for moving the same on its out stroke, a latch having an apertured head abutting the outer end of the plunger and held thereagainst by said spring and automatically engageable with said bar as said plunger moves on its return stroke to hold said plunger in partially completed stroke position, and a pin carried by and extending inwardly from said cap and adapted to engage said latch upon movement of said cap on said barrel toward its connected position on said barrel to move the latch laterally out of engagement with said stop and allow said spring to move said plunger to its full return

stroke position and thereby cause said displaced member to draw ink from said collector device into said reservoir.

11. A fountain pen comprising a barrel having an ink reservoir, ink feed means connected to said reservoir and including an overflow ink collector, means for filling said reservoir including a plunger reciprocable in said barrel and retracting means resiliently urging said plunger rearwardly of said barrel, a cap attached to the rear end of said barrel and removable for access to said plunger, means including a releasable latch element on said barrel for limiting full retracting movement of said plunger after a predetermined forward stroke thereof, and a release element on said cap positioned to engage and release said latch element upon replacement of said cap on said barrel and thereby permit said retracting means to effect full retracting movement of said plunger and cause said filling means to draw ink from said collector into said reservoir.
